UNITED STATES PATENT OFFICE.

CHARLES H. GAIL, OF CINCINNATI, OHIO, ASSIGNOR TO THE SHOTT MANUFACTURING COMPANY, OF CINCINNATI, OHIO, A CORPORATION OF OHIO.

BEDSPRING.

Application filed April 22, 1921. Serial No. 463,632.

To all whom it may concern:

Be it known that I, CHARLES H. GAIL, a citizen of the United States, residing at Cincinnati, in the county of Hamilton and 5 State of Ohio, have invented certain new and useful Improvements in Bedsprings, of which the following is a specification.

Simple and efficient means for fastening or securing the ends of short, horizontal, 10 connecting springs to the uppermost coils of the vertically arranged spiral-springs in a bed-spring or similar appliance in such manner that there will be an entire absence of noise in the use of the structure and in 15 which there is no possibility of the connecting springs becoming displaced even though the coils of the spiral-springs are not crimped or bent at the points of attachment constitutes the substance of the present in- 20 vention.

The manner in which these and other desirable objects and aims of the invention are attained in the actual practice of the invention will be readily comprehended by those 25 skilled in this art from a consideration of preferred embodiments of the invention illustrated in the accompanying drawing forming a part of this specification, the detailed description of the appliances shown 30 in such drawing being presented hereinbelow.

In the several views of this drawing the same parts have been supplied with like reference characters.

35 In the drawing:

Figure 1 is a fragmentary plan view of a small portion of a bed-spring or similar structure embodying the present invention;

Figure 2 is an enlarged cross-section on 40 line 2—2 of Figure 1, the parts being viewed as indicated by the arrows;

Figure 3 is a fragmentary plan view of a modified construction; and

Figure 4 is a view of the type of construction shown in Figure 3 and constitutes a 45 fragmentary section on an enlarged scale on line 4—4 of Figure 3.

Referring to the drawing, it will be perceived that the structure includes the usual 50 longitudinal and transverse rows of vertical, spiral or hour-glass springs 10, 10 supported, as is customary, at their lower ends on a suitable framework, not shown, and each having the regular, flat, top coil or convolution 11, with the common attachment 12 at

the end of the wire of which the spring is formed.

At their upper ends, these several springs are yieldingly or elastically connected together by helical-springs 13, 13, four being 60 used to fasten the top coil of each spiral-spring to its neighbors, all as is clearly illustrated.

At each of its opposite ends, each of such helical-springs has an elongated or other 65 appropriately-shaped loop 14 passing over and bearing on the wire forming the round top coil of the corresponding upright spiral-spring, the terminal portion 15 of the loop wire being bent down outside of such top 70 convolution, whereby there is no danger of its catching or tearing the mattress or other cushion adapted to rest on and be supported by the spring structure.

Each such loop is fastened to the correlated or complementary top coil on which it rests by a tie-wire 16 extended diametrically across the spiral-spring, each of its ends being bent to fasten the loop of the corresponding helical-spring in position. 75

Inasmuch as both ends of such securing wire are similarly bent to perform its holding or binding function, only one will be described in detail.

The wire 16 near the end under consideration is bent somewhat sidewise at 17 in a more or less oblique direction, then outwardly at 18 beneath the top coil wire, then upwardly at 19 at one side of the helical-spring end loop, then across the top of said 80 loop at 20, thence downward at 21 over the other side of the loop, then inward at 22 under the top coil 11, then up around and over the part 17 at 23 of the same wire, and then down in an inclined direction at 24 90 through and in contact with the end wall of the loop, all as is fully presented in Figures 1 and 2.

In this manner, the helical-spring is bound so securely endwise against the top coil of 100 the upright spring, and its loop is so firmly clamped to the wire forming such coil, that there is no danger of relative slippage or movement of the parts on one another, and hence there is no danger of the structure 105 squeaking or otherwise becoming noisy.

As has been indicated, the opposite ends of the wire 16 clamp two of the helical-springs to the same spiral-spring and in like manner a second cross-wire 25 disposed at 110

90 degrees to wire 16 and positioned either above or below the latter wire fastens two other helical connecting springs to the same top convolution of the upright spring.

5 It is not absolutely essential, although usually desirable, that the end of the fastening wire be bent around itself at 23, and, accordingly, in Figures 3 and 4 a somewhat modified construction has been presented.

10 In this case, the helical-spring and its loops are the same as in the preceding instances, but the end of the fastening wire is somewhat differently shaped.

Such wire 26 is bent sidewise aslant at 15 27 and then it passes under the top coil at 28, extending upwardly at 29 outside of such top ring, then it projects horizontally across the top of the loop at 30 and then down beyond its other side at 31.

20 It then continues inwardly at 32 under the top ring, then up at one side at 33 and over the top of one side wire of the loop at 34, and then down into the loop at 35.

25 It will be seen that this structure is practically or substantially like the other one except that the bending of the end of the clamping wire around the main body of the same is omitted.

30 In many cases this latter construction is adequately strong and obviously employs a lesser length of wire.

In both instances, the ends of the short helical-springs are very fixedly clamped or tied or attached to the main, load-supporting, vertically-disposed spiral-springs, and because of such construction, even though the upper convolutions or rings of the spiral-springs are uncrimped at the points of attachment of the short, horizontal, connecting springs, yet the elements are so adequately and firmly secured together that relative movement is impossible under normal conditions.

45 As in somewhat similar constructions, the short helical-springs not only yieldingly connect the spiral-springs together, but they act in some measure to support the superimposed mattress or other cushion, preventing it from unduly sagging between the upright springs, and the crossed securing wires extended across the upper ends of the vertically-disposed springs, perform a somewhat similar function in supporting the mattress or similar body and preventing it from becoming unduly depressed in the coils or interiors of the springs.

Obviously, the invention is not confined to the precise structures detailed herein, 60 since it is of broader scope as indicated by the appended claims by which it is defined.

Accordingly numerous minor changes may be incorporated in the bed-springs shown 65 without departing from the fundamental

principles on which the invention is based and without surrendering or foregoing any of its several structural and functional advantages.

I claim:

1. In a structure of the character described, the combination of a spiral-spring having a relatively-flat end convolution, a helical-spring having an end loop bearing on the wire forming said end convolution, 70 and means to substantially immovably secure said loop and convolution together, said loop and convolution being uncrimped at their points of attachment.

2. In a spring structure of the character described, the combination of a spiral-spring, a helical-spring having a terminal loop extended across and bearing on the wire forming the end coil of said spiral-spring, and a fastening wire extending 85 across said end coil wire on the side thereof opposite said loop, then at substantially right angles to the plane of said loop outside of said end coil, then across the side of said helical-spring loop not bearing on 90 said end coil, then substantially at right angles to the plane of said loop, then across said end coil wire, and through said helical-spring loop.

3. In a spring structure of the character described, the combination of a spiral-spring, a helical-spring having a terminal loop extended across and bearing on the wire forming the end coil of said spiral-spring, and a fastening wire extended across 100 said end coil wire on the side thereof opposite said loop, then at substantially right angles to the plane of and outside of said loop and also outside of said end coil, then across that side of said helical-spring loop 105 not bearing on said end coil, then substantially at right angles to the plane of said loop, then across said end coil wire on the side thereof opposite said loop, and through said helical-spring loop.

4. In a spring structure of the character described, the combination of an upright spiral-spring, a substantially-horizontal helical-spring having a terminal loop extended across and bearing on the top of the wire 115 forming the end coil of said spiral-spring, and a fastening wire extended below said end coil wire, then up outside of said loop and also outside of said end coil, then across the top of said helical-spring loop, then down outside of said loop and coil, then below said end coil wire, and up and down through said helical-spring loop.

5. In a spring structure of the character described, the combination of a spiral-spring, a helical-spring having a terminal loop extended across and bearing on the wire forming the end coil of said spiral-spring, and a fastening wire extended across 125 said end coil wire on the side thereof oppo-

- site said loop, then at substantially right angles to the plane of said loop outside of said end coil, then across that side of said helical-spring loop not bearing on said end coil, then substantially at right angles to the plane of said loop outside of said end coil, then across said end coil wire, then around said fastening wire, and then through said helical-spring loop. 35
- 5 6. In a spring structure of the character described, the combination of an upright spiral-spring, a helical-spring having a terminal loop extended across and bearing on the top of the wire forming the end coil of said spiral-spring, and a fastening wire extended across the bottom of said end coil wire, then up outside of said loop and also outside of said end coil, then across the top of said helical-spring loop, then down out- 40
- 10 side of said loop and coil, then across the bottom of said end coil wire, then around said fastening wire, and then through said helical-loop spring. 45
7. In a spring structure of the character described, the combination of a spiral-spring, a helical-spring having a terminal loop extended across and bearing on the wire forming the end coil of said spiral-spring, and a fastening wire having a por- 50
- 15 tion bent to one side, extended across said end coil wire on the side opposite said loop, 55
- then at substantially right angles to the plane of said loop outside of said end coil, then across that side of said helical-spring loop not bearing on said end coil, then substantially at right angles to the plane of and at the opposite edge of said loop, then across said end coil wire, then part way around the main body of said fastening wire, and then through said helical-spring loop. 40
8. In a spring structure of the character described, the combination of a spiral-spring having an end coil, a plurality of helical-springs having terminal loops extended across the wire forming said end coil, and a plurality of crossed fastening wires extended across said end coil having each end bent to secure the loop of one of said helical-springs to said end coil. 45
9. In a spring structure of the character described, the combination of a spiral-spring having an end coil, a plurality of helical springs having terminal loops extended across the wire forming said end coil, and a plurality of crossed fastening wires 50
- 20 extended across said end coil and each having each end bent to secure the loop of one of said helical-springs to said end coil, said end coil and loop being uncrimped at their points of attachment. 55

CHARLES H. GAIL.
